BRUSH AND MOUNTING THEREFOR

Application filed December 28, 1929. Serial No. 417,197.

The present invention relates to brushes and mountings therefor and more particularly to short-circuiting brushes for repulsion motors.

5 In the ordinary repulsion or repulsion-induction motor, the commutator is short-circuited at two or more points by one or more pairs of brushes. Each brush is mounted in a separate brush-holder and since the 10 brushes are not of great thickness, there is a tendency for them to chatter in their supports. This chattering not only causes noise but also prevents proper commutation. Moreover, inasmuch as the motors are usually 15 wound so that the generated voltage is low, special precautions must be taken to connect the brushes together with a minimum of electrical resistance, in order that the contact resistances may not unduly limit the 20 short-circuit current.

The object of the present invention is to provide a brush and a mounting therefor whereby any tendency to chatter is entirely 25 eliminated and also complete short-circuiting between the proper points of the commutator is effected.

With this object in view, the principal feature of the invention comprises a single brush member constructed to take the place of a pair 30 of brushes in the usual motor and being of yoke or U-shape, having spaced legs adapted to engage the commutator, which legs are rigidly connected together by a cross-piece 35 of low electrical resistance. In its preferred form, the invention comprises a single integral yoke-shaped piece of carbon or other conducting material having good commutating properties and so formed that the 40 legs are directly short-circuited without the use of electrical connections which might introduce contact resistances. Because this brush subtends a comparatively large arc of the commutator, all tendency to chattering is 45 eliminated.

Another feature of the invention comprises a mounting of simple and inexpensive construction by which the brush is retained in proper position with relation to 50 the commutator.

Other features of the invention consist in

certain novel features of construction, combinations, and arrangement of parts hereinafter described and claimed.

In the accompanying drawings, Fig. 1 is a sectional elevation of a repulsion motor 55 embodying the brush and brush support of the present invention, being a section on line 1—1 of Fig. 2; Fig. 2 is an end view of the motor with the end bonnet removed; Fig. 3 is a plan view of the brush assembly; 60 Fig. 4 is an end view of the assembly shown in Fig. 3; and Fig. 5 is a side elevation of the brush assembly.

The invention is herein illustrated and described as embodied in a four pole repulsion motor having provision for brush contacts with the commutator at intervals of 65 90°. The motor is illustrated as employing four brush contacts and utilizing two of the improved brush assemblies, although 70 for many purposes, a single pair of contacts is sufficient and one of the brush assemblies only need be employed.

The motor comprises the usual rotor 6, 75 the end bonnet 8, and the commutator 10. The commutator is engaged at four points by brushes 12. Each brush, as shown in detail in Fig. 4, is of yoke or U-shape having two legs 14 adapted for direct engagement with the commutator, the legs being 80 connected by an integral arch 16, subtending the entire angle between the legs. The entire brush, which takes the place of a pair of brushes in the usual motor, is formed of 85 a single integral piece of carbon or other good commutating material. In the four pole motor shown in Fig. 2, the brush legs subtend an angle of 90°.

The brush is mounted in a support 18 of 90 particularly simple construction, being formed from a single piece of sheet metal. As shown in Fig. 3, the support has an end face 20, sides 22, and feet 24. A channel for the brush is formed by inwardly extending projections 26 and 28 struck out from the material of the sides 22. The channel is of such form as to permit free movements 95 of the brush toward or away from the commutator but to restrain it against movement 100 in other directions. A pair of indentations

28 are formed in the ends of the channel to serve as positioning means for the brush. A spring fulcrum 30 is struck up from each side face 22 and turned inwardly. A spring 34 serves to press the brush toward the commutator. The spring is of wire having feet 36 symmetrically pressing on the outer surface of the arch 16 of the brush at points disposed somewhat inwardly from the legs 14. The spring is formed with coils 38 which are received on the fulcrums 30 and the ends of the springs are turned over the side faces of the support, as indicated at 40.

The feet 24 of the support are attached to an annular mounting plate 42 by a suitable means, preferably by spot welding. As shown in Fig. 1, the plate 42 in the form of a ring is received in an annular groove formed in the end bonnet of the motor. The position of the brushes may be varied by rotating the ring to any desired position. The ring is clamped in adjusted position by a bolt 43 passing through the end bonnet and screwing into a clamping nut 44 which engages the ring 42. The position of the ring is indicated by a pointer 46. Access to the ring for purpose of adjustment may be gained by removing the cover plate 48.

In the event that only a single brush assembly is employed, as may be the case in motors of the repulsion type, a mounting plate in the form of a complete ring is not necessary. The plate may then be cut in the shape of a sector, as indicated by the dotted lines 49 of the Fig. 4.

If the motor is to run as an induction rotor, after being brought up to speed as a repulsion motor, any suitable means may be provided for completely short-circuiting the commutator segments.

The advantages of the present invention are that the yoke-shaped brush which subtends a considerable arc of the commutator entirely eliminates any tendency to chatter, thus conducing to quiet operation and proper commutation. Also the electrical operation is improved because of the low resistance between short-circuited points of the commutator, there being no contact resistances except those interposed between the commutator and the brushes themselves. The construction is exceedingly simple in that only a single stamping and a single spring are necessary to form the complete brush-holder.

Having thus described the invention, what is claimed is:

1. The combination with a commutator, of a brush of yoke-shape having rigidly connected spaced legs adapted to separately engage spaced points of the commutator and to span the polar arc thereof.
2. The combination with a commutator, of a brush assembly comprising a rigid brush having spaced legs to span the polar arc of

the commutator, a mounting for the brush comprising a member having a channel in which the brush is received and adapted to permit movements of the brush as a whole toward and away from the commutator of the motor, and a spring engaging with the brush to press it toward the commutator. 70

3. The combination with a commutator, of a brush assembly comprising a rigid brush having spaced legs to separately engage the commutator and to span the polar arc thereof, a mounting for the brush comprising a single piece of sheet metal formed to provide a channel for the brush and having spring supporting projections, and a spring mounted on the projections and having portions symmetrically engaging the brush. 75 80

4. A brush assembly for a motor having, in combination, a rigid yoke-shaped brush member having spaced legs and a connecting arch, a brush mounting comprising an end face and side faces, projections turned inwardly from the side faces to form with the end face a channel to receive the brush member, and a spring supported on the brush mounting and having portions engaging the arch of the brush member. 90

5. In a repulsion motor having a frame, a rotor and a commutator, a brush assembly having, in combination, a rigid yoke-shaped brush member having spaced legs and a connecting arch, a brush mounting comprising a single piece of sheet metal formed with an end face and side faces, projections turned inwardly from the side faces to form with the end face a channel to receive the brush member, spring supporting projections turned inwardly from the side faces, a spring having coils supported by the projections and provided with feet engaging the arch of the brush member to press the brush toward the commutator, a plate to which the brush mounting is secured, and means for adjustably supporting the plate in the motor frame. 100 110

6. The combination with a motor having a commutator, of a brush comprising a single integral yoke having legs to subtend the polar arc of the commutator and an arch connecting the legs. 115

In testimony whereof I have signed my name to this specification.

CARLTON L. KENNEDY.
